DESIGN FOR A TOBACCO PIPE

Gedeon R. Comptois, New York, N. Y.

Application August 6, 1942, Serial No. 107,832

Term of patent 7 years

To all whom it may concern:

Be it known that I, Gedeon R. Comptois, a citizen of the United States, residing at New York, county of New York, N. Y., have invented a new, original, and ornamental Design for a Tobacco Pipe, of which the following is a specification, reference being had to the accompanying drawing, forming a part thereof.

Fig. 1 is a perspective view of a tobacco pipe, showing my new design.

Fig. 2 is a partial side elevational view thereof, showing the side opposite that illustrated in Fig. 1.

Fig. 3 is a bottom plan view of Fig. 1.

Fig. 4 is a similar view to Fig. 1, illustrating the pipe bowl alone.

Fig. 5 is a similar view to Fig. 4 looking from one side thereof.

Fig. 6 is a horizontal sectional view, taken on the line 6—6 of Fig. 2.

In Figs. 2, 4, 5 and 6 the stem and plug portions of the pipe are omitted for convenience of illustration.

I claim:

The ornamental design for a tobacco pipe, as shown.

GEDEON R. COMPTOIS,
